BENJAMIN D. KAY AND HENRY E. KAY, OF FALL RIVER, MASSACHUSETTS.

Letters Patent No. 83,859, dated November 10, 1868.

ADJUSTABLE BOX FOR ARBOR, &c.

The Schedule referred to in these Letters Patent and making part of the same.

To all whom it may concern:

Be it known that we, BENJAMIN D. KAY and HENRY E. KAY, of Fall River, in the county of Bristol, in the State of Massachusetts, have invented certain new and useful Improvements in Adjustable Boxes for Arbors, &c.; and we do hereby declare that the following is a full and exact description thereof.

Our box is provided with adjustable brasses, hinged to the casing, so that they cannot become permanently displaced or disarranged.

We will first proceed to describe what we consider the best means of carrying out our invention, and will afterwards designate the points which we believe to be new.

The accompanying drawings form a part of this specification.

Figure 1 is a central longitudinal section, and

Figure 2 is a cross-section.

Similar letters of reference indicate like parts in all the figures.

A is a case or shell, of cast-iron. M is a shaft or arbor, which it is important to run very accurately in the centre thereof, it being understood that the tension of the driving-belt, the strain of gear-wheels, or the resistance of the work which is being performed, may tend to move the arbor to one side, and thus to wear more rapidly in one direction than in another. Our improvement, while providing for adjusting the brasses, to compensate for the wear, holds the brasses hinged in position, so that they cannot become seriously disarranged.

B¹ B² B³ are bearing-pieces, or brasses, made of composition or other suitable material.

C, &c., are pointed screws, tapped through the ends of the casing A, and entering corresponding conical holes in the tails or connecting-pieces b, which connecting-pieces are hinged to the brasses, B¹, &c., by joints or hinges, b², thus forming a hinge-connection between the several brasses B¹ B² B³ and the rigid casing A.

Adjusting-screws, D¹ D² D³, are tapped through the casing A, at or near the centre, and adapted to press at or near the centre of the corresponding brasses.

The adapting of the brasses to receive the required

size of shaft or arbor will be readily understood. When, by use, the axis of the arbor M deviates from the centre of the casing A, it can be instantly readjusted by turning the proper screws, D¹ D², &c. The hinges which connect the brasses to the box allow the turning which is necessary, and the several brasses are moved up, either uniformly, or at the proper varying rate, as use gradually consumes and wears away the inner surfaces. When they are sufficiently worn down, the brasses may be exchanged, and the whole readjusted, as will be obvious.

One advantage of our improvement lies in the absolute rigidity with which we can hold the several brasses, after the proper adjustment has been attained, by simply tightening the hinge-bearings C. This makes the whole box as if formed in one piece, without any tremulous or rattling motion.

Another advantage lies in the certainty that the brasses cannot become stuck by friction, or become foul from any cause, and cannot be seriously misplaced, or lost in transportation.

Our improvement is more particularly designed for lathes for manufacturing spools, and analogous work, where it is important to hold the arbor exactly in the centre of the box in which the cutter is carried, and where a considerable side strain, due to the driving-belt, tends to wear the box always to one side, but it may obviously be applied in a great variety of machinery.

By using a wick, the box is easily made self-lubricating.

Having now fully described our invention, What we claim as new, and desire to secure by Letters Patent, is—

The brasses B¹ B², &c., hinged in the casing A, and arranged relatively to the arbor M, the hinge-screws C, and adjusting-screws D¹ D², or their equivalents, substantially as and for the purposes herein set forth.

BENJAMIN D. KAY.
HENRY E. KAY.
